CIRCUIT BREAKER

Joseph Stolz, Sachsenhausen-in-Mark, and Josef Hanke and Gottlob Lux, Berlin-Charlottenburg, and Richard Logstädt, Berlin-Schöneberg, Germany, assignors to Westinghouse Electric and Manufacturing Company, a corporation of Pennsylvania

Application October 14, 1932, Serial No. 637,764
In Germany October 17, 1931

19 Claims. (Cl. 200—88)

Our invention relates to electro-responsive apparatus suitable for use as a relay or as a circuit breaker trip device, and is particularly applicable to circuit breaker trip devices having a latch biased into engagement with the circuit breaker operating mechanism and having a thermally responsive and a magnetically responsive element for releasing the latch, the thermally responsive element releasing the latch and opening the breaker after a time delay upon the occurrence of a predetermined overload condition, and the magnetically responsive element releasing the latch and opening the breaker immediately upon the occurrence of a predetermined heavy overload condition.

It is an object of our invention to provide an improved device of this type that shall be more economical to manufacture, and that shall be more satisfactory and more reliable in operation than those devices which are already known to the art.

Another object of our invention is to provide an improved device of this type having a solenoid for attracting an armature, a spring for biasing the armature away from the solenoid, and a thermally responsive member for rendering the spring inoperative as a biasing member.

A further object of our invention is to provide an improved supporting mechanism for the armature of a magnetically responsive trip device; the improved supporting mechanism to include a spring for biasing the armature away from its attracting solenoid and a thermally responsive element which is operable upon the occurrence of predetermined electrical conditions to permit movement of the armature without overcoming the force of the biasing spring.

A further object of our invention is to provide an improved temperature compensating device for the thermally responsive element of circuit breaker trip mechanisms, or like apparatus, which shall cause the operation thereof to be independent of changes in the temperature of the surrounding medium.

A still further object of our invention is to provide an improved trip device for circuit breakers biased to the open position and held in the closed position by a releasable member which engages the trip device, our improved trip device to include a latch biased into engagement with the releasable member and an electro-responsive element for rendering the biasing force ineffective.

The principal field for immediate application of our invention is in connection with trip devices for circuit breakers used in controlling lighting

and distribution feeder circuits, and we shall hereinafter describe an embodiment of our invention as applied to such circuit breakers, without, however, in any way intending to restrict the scope of our invention except as indicated in the appended claims.

In this embodiment of our invention, we provide a manually operable mechanism for moving a switch member to the open or closed positions, a stationary contact member for cooperating with the movable switch member, an insulating base for mounting the various elements of the circuit breaker, an arc-extinguishing device affixed to the base adjacent the path of movement of the movable switch member, a means for biasing the switch member to the open position, a releasable restraining means for holding the switch member in the closed position, and a trip device for engaging and releasably restraining the means holding the switch member in the closed position.

The features of our invention which we believe to be new are particularly pointed out in the appended claims, and for a full understanding of the principles of the invention, reference may be had to the accompanying drawing, in which

Figure 1 is a plan view of a single pole circuit breaker embodying the principal elements of our invention; the cover has been removed and part of the operating member has been cut away to more clearly show the structural features involved.

Fig. 2 is a sectional view on the line II—II of Fig. 1.

Fig. 3 is a schematic perspective view showing the principal features of our invention as applied to the trip device of the circuit breaker shown in Figs. 1 and 2.

Fig. 4 is a schematic perspective view showing one modification of our invention.

Fig. 5 is an elevational view showing a modified form of thermally responsive element for use with our invention, and

Fig. 6 is a plan view of the thermally responsive element shown in Fig. 5.

Referring to the drawing, the base 1 is of moulded insulating material and has mounted thereon the terminal contacts 3 and 5, the trip device 7, the circuit breaker operating mechanism 9 which has associated therewith the switch member 11, the arc extinguisher 13, and the main stationary contact 15. The cover 17 is likewise of moulded insulated material and is fastened to the base 1 by means of two screws 19 which engage suitable threaded openings 21 in the base 1. The upper portion 25 of the operating member 23,

which is of moulded insulating material, has a projection 27 which extends through a suitable opening 29 in the cover 17 to permit manual operation of the circuit breaker mechanism. The various parts of the trip device 7 are mounted on suitable moulded projections extending upwardly from the base 1, through the agency of screw fastenings, as will be described in some detail later.

The electrical circuit through the breaker is very direct; beginning with the terminal contact 5, the current flows successively through the conducting strip 31, the stationary contact 15, the moving contact 33, the resilient conducting member 35, the flexible shunt 37, the energizing coil 39 for the magnetically responsive element of the trip device, the conducting strip 41 which connects one end of the coil 39 with the heater 43 for the thermally responsive trip element, the heater 43, the conducting strip 45, and thence to the terminal contact 3.

The switch member 11 has a channel shaped frame 47 which is pivoted to the U-shaped frame 63 of the circuit breaker operating mechanism 9 through the agency of the pivot pin 49. The resilient conducting member 35 is preferably constructed of spring steel, and as previously pointed out, the moving contact 33 is rigidly affixed to one end thereof by means of the screw 53. The other end of the conducting member 35 and one end of the flexible shunt 37 are fastened to the central portion of the channel shaped switch member frame 47 by means of the rivets 55. Round spacing washers 56 are provided to position the switch member frame 47 between the sides of the U.

We prefer to use arc-resisting material for the main contacts 15 and 33, the former being composed of finely divided silver and graphite compressed into a conglomerate mass, and the latter being composed of a silver-molybdenum alloy.

The arc extinguisher 13 is of the spaced-plate type in which a plurality of slotted magnetic plates, each insulated from the other and having a slot therein, are provided. The extinguisher is positioned adjacent the arc path—the slots being of substantially the same outline as the moving contact—and upon the establishment of an arc, due to the altering of the magnetic circuit adjacent to the arc path, force the arc into the spaces between the plates where it is quickly cooled and extinguished.

In the structure which we prefer to use, the magnetic plates 57, having slots 59 therein, are assembled between two end plates 61 of insulating material, projecting lugs (not shown) being provided in the magnetic plates 57 for engaging the end plates 61.

The operating mechanism 9 comprises, in general, a U-shaped base 63, a pair of toggle links 65 and 67 for actuating the frame 47 of the switch member 11, a releasable carrier member 71 for restraining the toggle links 65 and 67 in an operative position, the operating member 23, and the springs 73 for connecting the operating member 23 to the knee of the toggle links. The U-shaped base 63 is fastened to the insulating base 1 of the circuit breaker proper by means of two screws 75 which engage suitable threaded openings therein. The pivot pin 49 which provides a pivot point for the switch member 11 extends through aligned openings in the U-shaped base 63. Other holes are provided for the reception of the pivot pins 77—one on either side of the U—which provide pivot points for the bifurcated portion 79 of the operating member 23.

The lower end (with respect to the base 1) of

the toggle link 67 is pivoted to the frame 47 of the switch member 11 by means of the pivot pin 81. The upper end of the toggle link 67 is pivoted to one end of the second toggle link 65 by means of the knee pivot pin 83. One of the operating springs 73 engages each end of the knee pivot pin 83 and thus serves to operatively connect the knee of the toggle with the operating member 23. The carrier 71, which is pivoted about the pin 85, provides a releasable restraining means for holding the toggle links 65 and 67 in an operative position—the upper end (Fig. 2) of the toggle link 65 being pivotally fastened to the carrier 71 through the agency of the pin 87. The movement of the carrier 71 in a clockwise direction (Fig. 2) is limited by the projection 89 which extends inwardly from one side of the U-shaped base 63. The limits of movement of the bifurcated portion 79 of the operating member 23 are defined by the off-set projections 91 and 93 which extend upwardly from the U-shaped base 63.

As previously pointed out, the trip device 7 includes a magnetically responsive element 95 and a thermally responsive element 97. A latch 99 which is formed integral with the movable armature 101 of the magnetically responsive element 95 is provided for releasably engaging the end 98 of the carrier 71. The core member 103 of the magnetically responsive element 95 is held in place by two screws 105 which pass through suitable openings in the moulded member 107 extending upwardly (Fig. 2) from the base 1. The core 103 has a bifurcated portion 109 which provides a pivot point for the combined latch and armature 101, the pivot pin 110 being provided for engaging the armature 101. The single-turn energizing coil 39 is affixed to the base 1 by means of the screw 111 which also serves to electrically connect one end of the coil 39 with the conducting strip 41; the other end of the coil 39 is conductively fastened to one end of the flexible shunt 37.

As shown particularly in Figs. 2 and 3, the armature 101 supports, at its upper end, two relatively movable members 113 and 115 which are pivotally fastened to each other by means of the pivot pin 117. The member 113 has an upwardly projecting portion 119 and the member 115 has an upwardly projecting portion 121. A biasing spring 123 engages each of the portions 119 and 121 and thereby yieldably connects the two members 113 and 115. The member 115 has a portion 125 which extends outwardly from the pivot pin 117 and is adapted to engage a stop 127 fastened to the member 113. The engagement of this stop 127 and the projection 125 define the limit of relative movement of the members 113 and 115 in the direction toward which they are biased by the spring 123.

One end of the spring 123 is provided with a threaded portion 129 which engages the thumb nut 131 to provide a means for regulating the biasing force exerted by the spring 123 on the two members 113 and 115. A rod member 133 extends upwardly from the threaded portion 129 of the spring 123 and provides a convenient indicating means for showing the amount of stress to which the spring is subjected, a suitable opening 135 and indicator scale 137 being provided in the cover 17.

The thermally responsive element 97 includes a heater 43 of resistance material which is adapted to be connected in the electrical circuit through the agency of the screw fastenings 139. A bimetallic member 141 is thermally conductively joined to the heater 43 by means of two 75

rivets 143. The unfastened end of the bimetallic member 141 has a cutout portion 145 therein for engaging the movable portion 147 of the armature supporting latch 149. The bimetallic heater unit is completely removable and thereby provides a convenient means for changing the rating of the trip device.

The armature latching means 149 comprises a crank-shaped frame member 151 having a cylindrical opening 150 (Fig. 3) therein which provides a support and a guide for the movable portion 147. The central portion 153 of the movable member 147 is enlarged and threaded. This threaded enlargement provides a stop for limiting the movement of the movable member 147 toward the latched position. The upper end (Fig. 1) of the movable member 147 engages a guide opening 155 in an extension of the base 1 and is supported thereby. A spring 157 is positioned between that portion of the base 1 adjacent the guide opening 155 and the threaded portion 159 disposed on the enlarged threaded portion 153 of the movable member 149. This spring 157 biases the movable member 149 into the latched position. The lower end (Fig. 1) of the frame member 151 is supported by a bimetallic supporting member 161; by making the supporting member 161 of bimetallic material it is possible to secure a thermally responsive element which is not affected by changes in temperature in the surrounding medium. The movement of the support member exactly compensates for the movement of the electrically heated bimetallic trip member due to changes in room temperature. The spring 157 and the adjustable nut 159 provide a convenient means for controlling the time relay between the occurrence of an overload and the tripping point of the thermally responsive element.

The end 163 of the movable member 147 extends through the cylindrical guide opening 150 in the frame member 151 and is adapted to releasably engage the end 165 of the member 115 which is supported on the movable armature. The member 115 is biased to a position beneath the end portion 163 of the movable latch member 147 by the spring 167.

The operation of our invention may best be described in conjunction with Figs. 1 and 2 which show the circuit breaker in the closed position. To open the breaker manually the operating member 23 is moved counter-clockwise (Fig. 2) about its pivot pins 77. This movement of the operating handle causes the over-center springs 73 to exert a component of force on the knee pivot pin 83 tending to move that pin to the left (Fig. 2). And when this component becomes sufficiently large, the toggle links 65 and 67 collapse and thereby open the circuit breaker contacts with a snap action. The upper movement of the switch member 11 is limited by the engagement of the resilient conducting member 35 with the projection 89 on the frame 63.

To close the circuit breaker manually the operating handle 23 is moved clockwise about its pivot point until the component of force exerted by the over-center springs 73 is sufficiently large to set the knee of the toggle in motion toward the right (Fig. 2). The movement of the toggle during both the opening and the closing operation proceeds at a progressively increasing rate because the effective component of force increases as the knee of the toggle moves toward the closed or opened position. Thus the contacts are perfectly opened and closed with a snap action.

Upon the occurrence of a heavy overload or short circuit condition in the controlled circuit the attractive force exerted on the armature 101 by the energized core 103 becomes sufficiently large to move the armature against the force of the biasing spring 123, the member 113 moving with respect to the member 115 by pivoting about the pivot pin 117. This movement of the armature 101 causes the latch 99 to release the end 98 of the carrier member 71. The carrier 71 is biased about its pivot pin 85 in a clockwise direction (Fig. 2) by the over center springs 73, and begins to move in that direction as soon as it is released by the latch 99. The clockwise movement of the carrier 71 moves the upper pivot pin 87 to the right (Fig. 2) of the center line of the toggle; the over center springs 73 then cause the toggle to collapse and open the circuit breaker contacts in exactly the same manner as for manual operation.

Upon the occurrence of a moderate overload condition which does not energize the core 103 sufficiently to overcome the force of the biasing spring 123 and move the armature 101 to release the latch 99, the bimetallic member 141 begins to flex in a direction toward the threaded nut 159. If the overload continues for a sufficient length of time, the end 171 of the bimetallic member 141 engages the nut 159 and moves it together with the attached movable member 147 away from the frame member 151 against the biasing spring 157. After a short time, the end portion 163 of the member 147 disengages the end 165 of the movable member 115. The biasing spring 123 is then rendered inoperative as a biasing means for the armature 101—the spring 167 is relatively weak and exerts but a small force—and the attractive force of the energized core 103 is sufficient to move the armature and the two relatively movable members 113 and 115 supported thereon about the pivot pin 110 thereby causing the latch 99 to disengage the carrier 71. This disengagement of the latch 99 and the accompanying release of the carrier 71 permits the breaker contacts to open as described in the previous paragraph.

After the opening of the circuit breaker contacts by either the magnetically responsive trip element 95 or the thermally responsive trip element 97, it is necessary to restore the breaker mechanism to an operative position. To do this the operating handle 23 is moved counter-clockwise (Fig. 2) about its pivot 77; the projection 173 on the operating member 23 then engages the portion 175 of the carrier 71, and continued movement of the operating member causes the carrier to move clockwise about its pivot 85. When the operating member 23 has nearly reached the off position the portion 98 of the carrier 71 reengages the latch 99—the armature 101 being forced to move toward the core 103 in order to clear the latch 99.

The trip device 7 is entirely automatically resettable. If the breaker has been opened by the magnetically responsive trip element 95, the armature 101 is immediately moved back to the position shown in Fig. 2 by the biasing spring 123. If the breaker has been opened by the thermally responsive trip element 97, the armature 101 and the two relatively movable members 113 and 115 are restored to the position shown in Fig. 2 by the secondary biasing spring 167. It is important to note in this connection

that the lower edge of the portion 165 of the member 115 never moves above the upper edge of the end 163 of the movable member 147. Thus the member 115 will not be blocked against 5 downward movement following the opening of the breaker contacts and the accompanying removal of the force holding the movable member 147 out of engagement with the member 115.

The modification of our invention shown in 10 Fig. 4 is essentially similar to the construction shown in Figs. 1, 2 and 3. The bimetallic element 177 corresponding to the element 141 has been modified to serve as a support for the movable member 179 which corresponds to the 15 member 147, and a bimetallic compensating portion 181 has been substituted for the member 161. It will be seen that this modified construction is somewhat simpler than the previously described structure but the functioning is substantially the same.

The modified thermally responsive element 183 which is shown in Figs. 5 and 6 is intended for use in place of the heater 43 and the attached bimetallic member 141, the holes 185 being 20 adapted to engage the screw fastenings 139. This modified form of bimetal is an improvement over the two part structure previously described, in that the bimetallic member itself is used as a heater. Both types of thermally responsive elements are removable and interchangeable and permit the ready adjustment of the trip device to any desired ratings.

Should an attempt be made to close the breaker against an overload or against a short circuit condition the latch 99 will be released instantaneously or after a predetermined time delay, depending upon the magnitude of the overload, exactly as described before. The releasable carrier 71 will likewise be released and will cause 30 the toggle mechanism to break so as to open the circuit independent of the position of the operating handle. Therefore, it is not possible to hold the breaker closed against a continued overload or against a short circuit condition.

It will thus be seen that we have disclosed 40 an improved electro-responsive device which includes a thermally responsive element, a magnetically responsive element, a spring for biasing the armature of the magnetically responsive element away from the attracting means, and a means for rendering the spring ineffective as a biasing means. In addition we have disclosed 50 a means for compensating for changes in the temperature of the medium surrounding the thermally responsive element, and we have shown how this improved mechanism can be applied to a quick-make and quick-break circuit interrupter which is biased to the open position and is held in the closed position by a releasable carrier.

While in accordance with the patent statutes, we have given the foregoing details of a practical embodiment of our invention, it is to be understood that many of these are merely illustrative and that variations of their precise form 60 will be desirable in some applications. We desire therefore that the language of the accompanying claims be accorded the broadest reasonable construction and that our invention be limited only by what is explicitly stated in the claims and by the prior art.

We claim as our invention:

1. In electrical apparatus, an armature, magnetic means for attracting said armature, means 70 biasing said armature away from said attract-

ing means, electro-responsive means operable to permit said attracting means to move said armature without overcoming more than a fraction of the force normally exerted by said biasing means, and means for preventing the movement of said armature in response to the attraction of said magnetic means from subjecting said electro-responsive means to any substantial mechanical stress.

2. In electrical apparatus, a movable armature, 10 magnetic means for attracting said armature, means biasing said armature away from said attracting means, electro-responsive means, including a thermally responsive member, for causing a reduction in the biasing force normally exerted by said biasing means upon the 15 occurrence of predetermined electrical conditions, and a thermally responsive compensating means for making the operation of said thermally responsive member independent of variations 20 in the temperature of the surrounding medium.

3. In electrical apparatus, a movable armature, magnetic means for attracting said armature including a core member of magnetic material and a coil for energizing said core member, spring means biasing said armature away from said attracting means, electro-responsive means, including a thermally responsive member, for causing a reduction in the biasing force 25 normally exerted by said spring biasing means upon the occurrence of predetermined electrical conditions, and a thermally responsive compensating means having an element of bimetallic 30 thermally responsive material for making the operation of said electro-responsive means independent of variations in the temperature of the 35 surrounding medium.

4. In a trip device for a circuit interrupter, a magnetically responsive element for actuating the tripping mechanism immediately upon the occurrence 40 of predetermined heavy overload conditions in the controlled circuit, and a thermally responsive element for actuating the tripping mechanism after a time delay upon the occurrence of predetermined moderate overload conditions in the controlled circuit, said magnetically responsive element including a core member, an energizing winding therefor, and an armature yieldably held away from said core member by means including two interconnected relatively 50 movable members and a biasing spring which biases said members against relative movement in one direction, one end of one of said members being retained in position by releasable means 55 actuatable by said thermally responsive means to release said two interconnected members thereby permitting said armature to be attracted to said member without stressing said spring.

5. In a trip device for a circuit interrupter, a movable armature, magnetic means for attracting 60 said armature, means for holding said armature away from said attracting means including two interconnected relatively movable members, a spring for opposing relative movement of said members, and a means which includes a thermally 65 responsive element for releasably engaging said holding means, said thermally responsive element being operable to permit said armature to be attracted to said attracting means without stressing said spring upon the occurrence of predetermined electrical conditions, and said releasable 70 engaging means including means for preventing the movement of said armature in response to the attraction of said magnetic means from sub- 75

jecting said electro-responsive means to any substantial mechanical stress.

6. In a circuit interrupter, a switch member movable to open and closed positions, a movable operating member, a spring operatively connecting the operating member to the switch member, a releasable restraining means that is movable to an inoperative position for moving the switch member to open position, and a trip device for releasably engaging said restraining means, said trip device including a latch means for engaging said restraining means, a movable armature of magnetic material for actuating said latch, magnetic means, including a core member of magnetic material and an energizing coil for said core, for attracting said armature to release said latch, adjustable spring means for supplying a force for biasing said armature away from said attracting means, and electro-responsive means including a member of bimetallic material for reducing the biasing force normally exerted by said adjustable spring biasing means upon the occurrence of predetermined electrical conditions in the circuit controlled by said interrupter, said attracting means and said electro-responsive means being energized by the current flowing through said interrupter.

7. In a circuit interrupter, a switch member movable to open and closed positions, a movable operating member, a spring operatively connecting the operating member to the switch member, a releasable restraining means that is movable to an inoperative position for moving the switch member to open position, and a trip device for releasably engaging said restraining means, said trip device including a latch means for engaging said restraining means, a movable armature for actuating said latch, magnetic means for attracting said armature, means biasing said armature away from said attracting means, electro-responsive means, including a thermally responsive member, for reducing the force normally exerted by said biasing means upon the occurrence of predetermined electrical conditions to facilitate the operation of said trip device, and a thermally responsive compensating means for making the operation of said thermally responsive member independent of variations in the temperature of the medium surrounding said interrupter.

8. In electrical apparatus, an electro-responsive means movable to actuate said apparatus, spring means normally biasing said electro-responsive means against movement to actuate said apparatus, a second electro-responsive means actuatable to permit said first electro-responsive means to move to actuate said apparatus without having to overcome the biasing force normally exerted by said spring biasing means tending to prevent such movement, and means disposed intermediate said two electro-responsive means for preventing said last mentioned electro-responsive means from being subjected to any substantial mechanical stress during the operation of said first mentioned electro-responsive means.

9. In electrical apparatus, an armature, magnetic means for attracting said armature, means which normally prevents said magnetic means from moving said armature except when the attracting force exerted by said magnetic means reaches a predetermined large magnitude, electro-responsive means, including a bimetallic element, operable upon the occurrence of predetermined conditions to permit said attracting means to move said armature without overcoming more than a fraction of the force normally exerted by

said means which prevents said magnetic means from moving said armature, and means for preventing the movement of said armature in response to the attraction of said magnetic means from subjecting said bimetallic element to any substantial mechanical stress.

10. In electrical apparatus, an armature, magnetic means for attracting said armature, means biasing said armature away from said attracting means, an electro-responsive means, including a bimetallic element, operable upon the occurrence of predetermined conditions to permit said magnetic means to attract said armature without overcoming more than a fraction of the force normally exerted by said biasing means, and means for preventing the movement of said armature in response to the attraction of said magnetic means from subjecting said bimetallic element to any substantial mechanical stress.

11. In electrical apparatus, an armature, magnetic means for attracting said armature, means biasing said armature away from said attracting means, an electro-responsive means, including a bimetallic element, operable upon the occurrence of predetermined conditions to permit said magnetic means to attract said armature without overcoming more than a portion of the force normally exerted by said biasing means, and means for preventing the movement of said armature in response to the attraction of said magnetic means from subjecting said bimetallic element to any substantial mechanical stress, said means for preventing movement of said armature from stressing said bimetallic element comprising a slidably supported member positioned intermediate said bimetallic element and said armature and adapted to be moved in response to movement of said bimetallic element.

12. In a circuit interrupter, separable contact means for opening and for closing the electrical circuit through said interrupter, actuating means for moving said contact means from one position to the other, and an electro-responsive tripping means operable upon the occurrence of predetermined condition to cause said actuating means to move said contact means to the open circuit position, said tripping means including a movable armature, a solenoid means for attracting said armature, means which normally prevents said armature from being attracted toward said solenoid means except upon the occurrence of a predetermined large overload, electro-responsive means operable upon the occurrence of predetermined small overloads which persist for a substantial period of time to allow said solenoid means to attract said armature without overcoming more than a small portion of the force which normally prevents said armature from being attracted toward said solenoid means, and means intermediate said electro-responsive means and said armature which permits said armature to be moved by said solenoid means without subjecting said electro-responsive means to any substantial mechanical stress.

13. In a circuit interrupter, separable contact means for opening and for closing the electrical circuit through said interrupter, actuating means for moving said contact means from one position to the other, and an electro-responsive tripping means operable upon the occurrence of predetermined conditions to cause said actuating means to move said contact means to the open circuit position, said tripping means including a movable armature, a solenoid means for attracting said armature, means which normally prevents said

- armature from being attracted toward said solenoid except upon the occurrence of predetermined large current magnitude overloads, and a current-carrying electro-responsive means, including a bimetallic element and a member disposed intermediate said bimetallic element and said armature, operable upon the occurrence of predetermined small current magnitude overloads, which persist for a substantial period of time, to 5 allow said solenoid means to attract said armature without overcoming more than a portion of the force which normally prevents said armature from being attracted toward said solenoid means, said intermediate member allowing said armature to be moved independently of said bimetallic element.
14. In a circuit interrupter, separable contact means for opening and for closing the electrical circuit through said interrupter, actuating means 10 for moving said contact means from one position to the other, and an electro-responsive tripping means operable upon the occurrence of predetermined conditions to cause said actuating means to move said contact means to the open circuit position, said tripping means including an armature which is movable to actuate said tripping means, magnetic means for attracting said armature, means biasing said armature away from said attracting means, a bimetallic element operable upon the occurrence of predetermined conditions to permit said magnetic means to attract 15 said armature without overcoming more than a portion of the force normally exerted by said biasing means, and means for preventing the movement of said armature in response to the attraction of said magnetic means from subjecting said bimetallic element to any substantial mechanical stress.
15. In electrical apparatus, an armature, magnetic means for attracting said armature, means biasing said armature away from said attracting means, electro-responsive means operable to permit said attracting means to move said armature without overcoming more than a fraction of 20 the force normally exerted by said biasing means, and means disposed intermediate said electro-responsive means and said armature for preventing the movement of said armature in response to the attraction of said magnetic means from subjecting said electro-responsive means to any substantial mechanical stress.
16. In electrical apparatus, an armature, magnetic means for attracting said armature, means biasing said armature away from said attracting means, a latch movable from a normal latched 25

position to an unlatched position to permit said attracting means to move said armature without overcoming more than a fraction of the force normally exerted by said biasing means, and an electro-responsive means operable to move said latch from said latched to said unlatched position. 5

17. In electrical apparatus, an armature, magnetic means for attracting said armature, spring means biasing said armature away from said attracting means, electro-responsive means, which includes a movable member of bimetallic material, operable upon the occurrence of predetermined conditions to permit said attracting means to move said armature without overcoming more than a fraction of the force normally exerted by said spring biasing means, and means disposed intermediate said electro-responsive means and said armature for preventing the movement of said armature in response to the attraction of 10 said magnetic means from subjecting said movable bimetallic element to any substantial mechanical stress.

18. In electrical apparatus, an armature, magnetic means for attracting said armature, means biasing said armature away from said attracting means, electro-responsive means operable to permit said attracting means to move said armature without overcoming more than a fraction of the force normally exerted by said biasing means, 15 and a thermally responsive compensating means for making the operation of said thermally responsive means independent of variations in the temperature of the surrounding medium.

19. In electrical apparatus, an armature, magnetic means for attracting said armature, means biasing said armature away from said attracting means, an electro-responsive means including a bimetallic element operable upon the occurrence of predetermined conditions to permit said magnetic means to attract said armature without overcoming more than a fraction of the force normally exerted by said biasing means, means for preventing the movement of said armature in response to the attraction of said magnetic means from subjecting said bimetallic element to any substantial mechanical stress, and thermally responsive compensating means for making the operation of said electro-responsive means independent of variations in temperature of the surrounding medium. 35
